[57] CLAIM

The ornamental design for a display rack module, substantially as shown and described.

DESCRIPTION

FIG. 1 is a front elevational view of the display rack module showing my new design;

FIG. 2 is a top plan view thereof;

FIG. 3 is a side elevational view thereof;

FIG. 4 is a bottom plan view;

FIG. 5 is a front elevational view of a second embodiment of the design of FIG. 1, the top and bottom being identical to FIGS. 2 and 4;

FIG. 6 is a side elevational view of FIG. 5.

The rear of both embodiments follows the contours disclosed in FIGS. 1 and 5.
